UNITED STATES PATENT OFFICE.

THOMAS R. BLANCHARD AND EDWARD B. KENEFIC, OF MINNEAPOLIS, MINNESOTA.

RETORT FURNACE.

1,420,958.

Specification of Letters Patent. Patented June 27, 1922.

Application filed November 17, 1921. Serial No. 515,822.

To all whom it may concern:

Be it known that we, THOMAS R. BLANCHARD and EDWARD B. KENEFIC, citizens of the United States, residing at Minneapolis, in 5 the county of Hennepin and State of Minnesota, have invented certain new and useful Improvements in Retort Furnaces, of which the following is a specification.

Our invention relates to retort furnaces.

10 An object is to provide an apparatus which includes an improved retort so constructed that economical and satisfactory distillation of material such as straw and other vegetable substance may be effected, the carbon produced being retained in the retort for removal therefrom when the distillation is completed and the volatile content being driven off in the form of a byproduct which may be saved for use.

15 The full objects and advantages of our invention will appear in connection with the detailed description, and the novel features of our inventive idea will be particularly pointed out in the claims.

20 In the accompanying drawings which illustrate the application of our invention in one form, Fig. 1 is a view of the apparatus in vertical longitudinal section. Fig. 2 is a view in horizontal section on the line 2—2 30 of Fig. 3. Fig. 3 is a front elevational view.

Referring to the construction shown in the drawings, the numeral 10 designates a furnace wall within which is a heat supplying chamber or fire chamber 12 lying 35 above a grate 14. Below this grate is an ash pit 16 provided with a door 18. At the front of the fire chamber 12 is an opening 20 surrounding which is a hollow outwardly extending member 22 which is provided with 40 a damperlike door 24 pivoted at its upper end within the hollow member 22. Within the upper portion of the furnace wall and located above the fire chamber 12 is a retort 26 which is shown cylindrical for a large 45 portion of its extent. The front of the retort chamber 28 is provided with a hinged door 30 having a handle 32 by which it may be opened and closed. Above the retort chamber 28 is a horizontal longitudinally extending flue 34 which is connected with the fire chamber 12 by a number of pairs of flues 36, 38, and 40, there being three of these pairs in the embodiment shown. These inclined flues which are preferably oval in 55 cross-section, extend through the body of the retort in upwardly convergent direction

and, as will appear from Fig. 3, each pair of flues is in the form of an inverted V. Located in the flue 34 between the openings of successive pairs of the inclined flues are 60 control dampers 42 and 44, the latter being shown in open position and the former in closed position. The rear of the horizontal flue 34 is upwardly curved so as to lead into a smoke stack 46 containing a draft control 65 damper 48. The rear of the retort chamber 28 is provided with a byproduct outlet to which is connected a pipe 50 containing an outwardly opening check valve 52.

The operation and advantages of our invention will be readily apparent from the foregoing description. The straw or other material which is to be distilled is introduced into the retort chamber 28 through the opening controlled by the door 30. The 70 fuel for providing the heat is introduced on to the grate through the opening controlled by the door 24. The heat which is produced by the combustion of the fuel is concentrated upon the material contained in the retort 75 chamber 28 on account of the fact that the flues leading from the fire chamber extend through the body of the retort. The heat is very effectively concentrated within the retort chamber by means of the inclined flues 80 extending through the body of the retort and which open into the upper horizontal flue which is located just above the retort chamber. Whenever it is desired to supply increased heat to the rear portion of the retort, 85 the damper 44 is opened, and the damper 42 is closed as shown in Fig. 2. Upon opening the damper 42 more heat will be supplied to the front portion of the retort. If the damper 44 is closed, the heat will concentrate 90 still further toward the rear portion of the retort. The draft may be regulated by means of the damper 48 in the smoke stack. During the distillation process, the volatile content of the material being distilled will 95 pass in the form of gas out through the pipe 50 controlled by the check valve 52 so that there can be no return into the retort through this pipe. This gas may be utilized as a by-product.

105 We claim:

1. A retort furnace comprising a retort, a heat supplying chamber under said retort, a horizontal flue extending at the upper side of said retort, flues which extend through 110 the body of said retort and open into said horizontal flue at different positions, and

dampers in said horizontal flues located between the openings of successive flues.

2. A retort furnace comprising a horizontally extending retort, a heat supplying chamber under said retort, a horizontal flue extending at the upper side of said retort, and pairs of upwardly convergent flues which are oval in cross section and extend through the body of said retort and connect 10 said heat supplying chamber with said horizontal flue.

3. A retort furnace comprising a retort, a heat supplying chamber under said retort, a

horizontal flue extending at the upper side of said retort, pairs of upwardly convergent 15 flues which extend through the body of said retort and open into said horizontal flue at different positions along the length thereof, and dampers in said horizontal flue located between the openings of successive pairs of 20 flues.

In testimony whereof we hereunto affix our signatures.

THOMAS R. BLANCHARD.
EDWARD B. KENEFIC.
